UNITED STATES PATENT OFFICE.

CARL A. BEACH, OF DENVER, COLORADO.

AUTOMOBILE CABINET.

Application filed October 5, 1922. Serial No. 592,498.

To all whom it may concern:

Be it known that I, CARL A. BEACH, a citizen of the United States, residing at Denver, in the county of Denver and State 5 of Colorado, have invented certain new and useful Improvements in Automobile Cabinets; and I do declare the following to be a full, clear, and exact description of the invention, such as will enable others skilled in 10 the art to which it appertains to make and use the same.

This invention relates to an improved cabinet for use in connection with an automobile and one object of the invention is to 15 provide a cabinet which can be conveniently carried upon the running board or at the back of the body portion of the automobile and may contain cooking utensils, food, and tableware, the cabinet being further so constructed that it may be set up upon the 20 ground and the closure door for the cabinet swung downwardly to provide a table.

Another object of the invention is to provide the cabinet with improved supporting 25 legs for the body portion thereof, these legs being hingedly mounted beneath the cabinet and provided with improved means for retaining them in an extended or operative position.

Another object of the invention is to provide the door with improved supporting 30 legs hingedly mounted to permit of them being swung downwardly to an operative position when the door is lowered to form the table, improved means being provided 35 to retain the supporting legs in the operative position.

Another object of the invention is to so 40 construct this door that it may be extended similar to the top of an extension table and extra leaves put in to provide a long table when desired.

Another object of the invention is to provide the cabinet with a top which may be 45 swung upwardly to permit access to a chamber in the top portion of the cabinet and to have the top and table forming door so mounted that when swung to a closed position, their free end portions will be near 50 each other thus permitting a common fastener to be made use of to secure both the top and the swinging door.

Another object of the invention is to provide a cabinet which when not in use will

be compact and take up a small amount of 55 room, the folding legs being so mounted that they may be swung close against the swinging door and bottom of the cabinet where they will be out of the way.

This invention is illustrated in the accompanying drawings, wherein:

Figure 1 is a view showing the cabinet in front elevation with the swinging door closed and the folding legs swung to the inoperative position.

Figure 2 is a vertical sectional view taken along the line 2—2 of Fig. 1.

Figure 3 is a vertical sectional view through the cabinet when in position for use.

Figure 4 is a sectional view taken along the line 4—4 of Fig. 3.

Figure 5 is a vertical sectional view taken along the line 5—5 of Fig. 3 and looking towards the body of the cabinet.

Figure 6 is a fragmentary sectional view taken along the line 6—6 of Fig. 3, to show the manner of hingedly mounting the legs beneath the cabinet and the means for releasably retaining them in an operative position.

Figure 7 is a view similar to Fig. 3 with the swinging door in closed position.

Figure 8 is a bottom plan view of the cabinet taken along the line 8—8 of Fig. 3.

Figure 9 is a bottom plan view of the cabinet with the supporting legs swung upwardly to the inoperative position and the swinging door closed.

Figure 10 is a longitudinal sectional view 90 through the swinging door when in position for use as a table.

This improved cabinet is provided with a body 1 having partitions 2 and shelves 3 mounted therein so that cooking utensils, 95 containers for food, and other articles may be placed in the cabinet. It will of course be understood that the interior of the cabinet can be divided into as many compartments as desired according to the size of 100 cabinet built. A partition 4 is provided in the upper portion of this cabinet thus providing an upper compartment 5 in which extra leaves 6 may be placed when not in use in connection with the table. A top or cover 7 is hingedly mounted at the back of the cabinet as shown at 8 and when swung downwardly will close the compartment 5.

This cover 7 is provided with a hasp 9 having an opening to receive the eye 10 through which a fastener such as the padlock 11 will be passed.

5 The front of this cabinet is open and will be closed by a swinging door which is hingedly mounted at its lower end by means of hinges 12. This door which is normally of a proper size to fit into the open front of the 10 cabinet is provided with an inner or lower section 13 and an upper or outer section 14, each of which is preferably formed of a single board but may of course be formed of a plurality of boards suitably connected. 15 Strips 15 and 16 are secured respectively to the sections 13 and 14 of the door and one set of strips will be provided with tongues 17 for fitting into grooves formed in the second set as shown in Fig. 4 to permit the 20 strips 15 and 16 to slide longitudinally of each other and at the same time be prevented from moving out of engagement with each other until entirely drawn apart. Therefore, the section 14 may be drawn 25 away from the section 13 and one or more of the leaves 6 put in place in the same manner that leaves are placed in an extension table. At its free end, the section 14 is provided with a hasp 18 which is similar to the hasp 9 30 and will be swung into engagement with the eye 10 when the door is in the raised position so that the eye 10 and lock 11 through engagement with the two hasps 9 and 18 may serve to secure both the top 7 and the 35 front door in a closed position.

In order to support the free end portion 40 of the front door, there has been provided supporting legs 19 which are connected by a cross bar 20 and extend beyond this cross bar so that they may be pivotally connected 45 with the ends of the extended portion 21 of the cross bar 22 secured to the free end portion of the door section 14. It should be noted that the shoulder portion 21 has its 50 ends terminating short of the ends of the cross bar so that the supporting legs 19 may be swung to the position shown in Fig. 3 and be braced against further outward movement when in this position. In order to provide 55 means for yieldably retaining the supporting legs in an adjusted position, there has been provided spring strips 23 which may be formed of any suitable material and will be secured upon the block 24 carried by the 60 door section 14. The free end of the strip 23 extends across the cross strip 20 onto the shoulder 21 and will therefore serve to retain the supporting legs in the folded position shown in Figs. 1 and 2. When the sup- 65 porting legs are swung to the operative position, the free end portions of the securing strips will move into the pockets 25 and will securely hold the legs in the operative position, until the strips are swung out of the 70 pockets. Therefore, the supporting legs

cannot accidentally move towards a folded position and leave the free end portion of the table unsupported.

In order to support the cabinet, there has been provided supporting legs 26 which are 70 arranged at the ends of the cabinet in pairs connected by cross bars 27. These cross bars 27 are placed in spaced relation to the ends of the supporting legs so that the ends of the legs 26 can extend upon opposite sides 75 of a block 28 which is secured to the bottom of the cabinet as shown in Fig. 6. A spring strip 29 extends longitudinally of the bottom of this cabinet and is secured intermediate its length to a block 30 and has its 80 end portions extending as shown in Fig. 6 and also shown in Figs. 8 and 9. From an inspection of Fig. 9, it will be seen that when the supporting legs are folded against the bottom, the end portions of the strip 29 85 will extend across the strips 27 and rest against the block 28. When, however, the supporting legs are swung downwardly to the operative position, the end portions of the strip 29 will rest in the pockets 31 of the 90 strips 27 and the supporting legs will be held against swinging upwardly to the inoperative position. In order to firmly brace the supporting legs 26 against tendency to move towards the folded position, there has been 95 provided bracing yokes 32 which are pivotally mounted as shown at 33 and have their arms terminating in hooked end portions 34 for fitting into sockets formed in the legs 26. Since the yokes are formed of resilient 100 material, it will be readily seen that the arms thereof can be readily moved into and out of bracing engagement with the supporting legs. When this cabinet is set up for use as a table as shown in Figs. 3 and 10, the supporting legs 19 and 26 are to rest upon the ground. The ground may be uneven and therefore each of the legs 19 and 26 has been 105 provided with a ground-engaging foot 35 provided with a threaded shank which extends into a threaded socket 36 formed in the leg. By proper adjustment, the feet may be allowed to rest upon the ground and the table held level.

When this cabinet is in use, the food 115 containers and cooking and table articles will be placed in the compartments shown in Fig. 5. The door for the open front of the cabinet can then be swung closed and secured against dropping by the clips 37. After everything has been put in place, the 120 hasp 18 can be swung onto the eye 10 over the hasp 9 and the padlock 11 then put in place. The cabinet can then be put in place upon the running board or upon the rear portion of the automobile body and suitably secured. When the cabinet is to be used, it will be removed from the automobile and the supporting legs 26 swung downwardly to the 125 operative position shown and the braces 32 130

5 moved into engagement with the supporting legs. The cabinet can then be set up upon the ground with the supporting legs resting upon the ground and supporting the cabinet in an elevated position. The padlock 11 will then be removed and the clips 37 swung out of the way so that the door can be swung downwardly. The supporting legs 19 can be swung to the operative position 10 shown in Fig. 3 either before the door is swung downwardly or afterwards. When the door is swung downwardly to the position shown in Fig. 3 with the supporting legs resting upon the ground, the brace rod 38 15 which is pivotally connected with one of the partitions 2 will be swung out and its hooked free end portion moved into engagement with the eye 39 carried by the section 13 of the door. The door when in this position forms a table upon which the plates and other articles will be placed. If it is found that the table is too small, the section 14 can be drawn away from the section 13 and one or more of the leaves 6 put in place 20 as shown in Fig. 10 thus lengthening the table. When use of the cabinet is no longer desired, the leaves 6 can be removed and replaced in the compartment 5 and after the food containers and cooking and table 25 articles have been replaced, the door can be swung upwardly to the closed position and first secured by the clips 37. The supporting legs 19 can then be released and swung downwardly to the closed position and the 30 hasp 18 then swung upwardly to engage the eye 10. The padlock would then be replaced. After the padlock has been secured, the cabinet can be turned rearwardly onto the ground and the braces 32 moved to release the supporting legs 26. The braces 35 will then be swung to the folded position shown in Fig. 9 and after the end portions of the strip 29 have been swung to an inoperative position, the supporting legs will 40 be swung to the folded position where they will be positioned flat against the bottom of the cabinet and out of the way as shown in Fig. 2. The cabinet can then be picked up by means of the handles 40 and put back 45 upon the automobile. It will thus be seen that this cabinet will be very convenient to use and further will be so constructed that it will be compact and there will be no parts extending to get in the way. It will be 50 further noted that the same locking means may be provided for securing the top 7 and front door. The top may have its inner 55 face provided with straps so that mirrors, brushes, razors and other toilet articles may 60 be held in engagement with the top. The straps will preferably be formed of rubber but of course may be formed of any suitable material desired. It will be obvious that if desired, the back of the cabinet may be provided with a swinging door similar to that 65 used for closing the open front, thus permitting a table to be provided at each side of the cabinet. As illustrated, the cabinet has been shown formed of wood, but it will be obvious that if desired, it can be 70 formed of metal or any other suitable material.

75 I claim:

1. In a structure of the character described, a cabinet open at its front and top, a cover for the open top hingedly mounted at one edge, a closure door for the open front of said cabinet hingedly mounted at its lower edge, a fastener carrier carried by said cabinet, and means carried by the free edge portions of said door and cover for engaging said fastener carrier to hold the door and cover closed. 80

85 2. In a structure of the character described, a cabinet open at its front and top, a cover for the open top hingedly mounted at one edge, a closure door for the open front of said cabinet hingedly mounted at its lower edge, an eye carried by said cabinet, and hasps carried by said cover and closure door for engaging said eye and holding the cover and door closed when a fastener is placed in engagement with said eye. 90

95 3. A cabinet open at its front, a closure door for the open front hingedly mounted at its lower end for swinging downwardly to a table forming position when opened, a cross bar extending transversely of the free end portion of said door, supporting legs pivotally connected with said strip for swinging into and out of an operative position, a cross bar connecting and bracing said legs, and a spring strip secured to said door and extending longitudinally thereof and having its free end extending in overlapping relation to the last mentioned cross bar to engage the same and releasably hold the legs in an operative or inoperative position. 100

105 4. The structure of claim 3 having the cross bar of the door provided with a side extension terminating short of the ends of the cross bar and having the legs pivotally connected with its ends and limited in their swinging towards an operative position through engagement with the extended end portions of said cross bar. 110

115 5. The structure of claim 3 and an eye secured upon said door adjacent the hinged end thereof, and a supporting rod pivotally connected with said cabinet and having a hooked free end for engaging said eye and bracing the door when in a lowered table-forming position. 120

125 6. A cabinet open at its front, a closure for the open front movable to an open position, supporting legs pivotally mounted in sets beneath opposite ends of said cabinet, a cross bar connecting the legs of each set to brace the legs, a spring strip secured intermediate its length beneath said cabinet and 130

having its free end portions engaging the bracing bars for releasably securing the legs in adjusted positions, and U-shaped yokes positioned beneath the cabinet and straddling said spring strips and pivotally mounted for swinging movement longitudinally of the spring strip, said yokes having

their arms terminating in hooked ends for engaging the legs and bracing the legs in an operative position.

10

In testimony whereof I have hereunto affixed my signature.

CARL A. BEACH.
